Frederick S. Williams

- projected substantially horizontally by the jets from the ports 25 that have risen above the floor level. The fluid is thus widely expanded and forms billows of gas that may be picked up by suction of the fire. The lid 22 serves the dual purpose of closing the recess 23 and baffling the discharge. The velocity of the gas is reduced to such an extent as substantially to preclude the entrainment of air.
- 10 The cap 20 coacts with the flange 24 to limit the rise of the cover. When the supply of extinguishing fluid nears depletion and the pressure falls the cover will drop by gravity to closed position. The outlets are therefore self-closing as well as self-opening so that after a fire or a test operation of the extinguishing system the floor will be restored automatically to normal condition with no projecting lids or open cavities to trip the attendants.
- 15 20 My invention is peculiarly adapted for the protection of hangars, but it is equally applicable to other enclosures and also to open areas, such as the decks of ships, air-craft carriers, etc., on which highly inflammable cargo or apparatus is stored. The term "floor" as used in the claims is to be interpreted as comprising any supporting surface.
- I wish it to be understood that the embodiment described above is to be taken as illustrative and not limitative of my invention and that I reserve the right to make such changes in form, construction, and arrangement of parts as fall within the spirit and scope of the following claims.
- I claim:
- 30 35 1. A method of extinguishing fire in a space having a floor which consists in discharging below the floor level jets of fire extinguishing fluid liquefied under pressure, expanding the liquid into a gas, discharging the expanding gas 40 through the floor, and with other jets of the extinguishing fluid discharging above the floor level spreading the expanding gas horizontally along the floor whence the expanded fluid may be drawn into the fire by suction produced by the 45 fire.

2. The method of extinguishing a fire in a space having a floor which consists in discharging below the floor level and at a plurality of points distributed throughout the floor jets of fire extinguishing fluid liquefied under pressure, expanding the liquid into a gas, discharging the same through the floor, baffling the expanding gas against vertical rise at a predetermined height above the floor level, and with other jets of the extinguishing fluid discharging above the floor 10 level spreading the gas horizontally along the floor, whence the expanded fluid may be drawn into the fire by suction produced by the fire.

3. In a fire extinguishing system a floor outlet for a fire extinguishing fluid liquefied under pressure, said outlet comprising an expansion chamber, a lid normally closing the top of the chamber, a cylinder, a tubular plunger slideable in the cylinder and secured at its upper end to the lid but open at its lower end to the cylinder, means 20 for leading the extinguishing fluid under pressure to the cylinder to raise the lid, and means for limiting the rise of the lid, the plunger being formed with lateral discharge ports in position to discharge the fluid laterally into the expansion 25 chamber when the plunger is in raised position.

4. In a fire extinguishing system a floor outlet for a fire extinguishing fluid liquefied under pressure, said outlet comprising an expansion chamber, a lid normally closing the top of the chamber, a cylinder, a tubular plunger slideable in the cylinder and secured at its upper end to the lid the plunger being open at its lower end to the cylinder, means for leading the extinguishing fluid under pressure to the cylinder to raise the 30 lid, and means for limiting the rise of the lid, the plunger being formed with lateral discharge ports, certain of which, when the plunger is raised, will be in position to discharge part of the fluid laterally into the expansion chamber and others of which will be above the chamber in position to spread horizontally the fluid discharging from the chamber.
